Patented Nov. 16, 1920.

3 SHEETS—SHEET 3.

UNITED STATES PATENT OFFICE.

JOHN E. ALEXANDER, OF PORT EDWARDS, WISCONSIN.

LONGITUDINAL DRIER FOR PAPER-MAKING MACHINES.

1,359,141.

Specification of Letters Patent. Patented Nov. 16, 1920.

Application filed November 26, 1917. Serial No. 204,086.

To all whom it may concern:

Be it known that I, JOHN E. ALEXANDER, a citizen of the United States, and a resident of the village of Port Edwards, in the 5 county of Wood and State of Wisconsin, have invented certain new and useful Improvements in Longitudinal Driers for Paper-Making Machines; and I do hereby declare that the following is a full, clear, 10 and exact description of the same, reference being had to the accompanying drawings, and to the numerals of reference marked thereon, which form a part of this specification.

15 This invention relates to an improved form of a drier unit for paper-making machines wherein a paper web to be dried is conducted longitudinally through a casing on longitudinally arranged belt conveyers 20 and between electric heating units. The heating units are adapted to heat air drawn through the casing by means of suction pumps, thereby permitting said heated air to uniformly dry the paper web in its passage 25 through the drier.

It is an object of this invention to construct a drier unit for a paper-making machine, said drier unit having the mechanisms thereof arranged longitudinally 30 therein.

It is also an object of this invention to provide an electrically heated drier unit through which a web to be dried is carried longitudinally in a straight path.

35 A further object of the invention is the construction of a drier unit adapted to permit a web to be conveyed through the casing of said drier unit in a straight path and through a current of electrically heated air.

40 It is an important object of this invention to construct a paper-making machine drier unit wherein a web is uniformly dried during its longitudinal passage through the drier unit on endless belts between electric 45 heating elements and through a continuous current of heated air.

Other and further important objects of this invention will be apparent from the disclosures in the drawings and specification.

50 The invention (in a preferred form) is illustrated in the drawings and hereinafter more fully described.

On the drawings:

55 Figure 1 is a side elevational view, partly

broken away, of a drier unit embodying the principles of this invention.

Fig. 2 is a top plan view thereof.

Fig. 3 is a section taken on line 3—3, of Fig. 2, with parts broken away.

Fig. 4 is a section taken on line 4—4, of Fig. 3, with parts broken away and parts shown in elevation.

Fig. 5 is an enlarged section taken on line 5—5, of Fig. 3.

Fig. 6 is an enlarged fragmentary detail section taken on line 6—6, of Fig. 5, with parts omitted and broken away.

Fig. 7 is a reduced detail view taken on line 7—7, of Fig. 6.

Fig. 8 is an enlarged detail view taken on line 8—8, of Fig. 4, with parts omitted.

Fig. 9 is a fragmentary section taken on line 9—9, of Fig. 8.

Fig. 10 is a vertical detail section taken through one of the heating units.

Fig. 11 is a wiring diagram of one of the heating units.

Fig. 12 discloses a modified form of a wire mesh conveyer having belts of different wire mesh.

As shown on the drawings:

The reference numeral 1, designates a floor or foundation upon which is rigidly mounted a framework 2, supported by integral legs or standards 3. Securely mounted within said framework 2, is a long comparatively shallow closed box or casing 4, having an inlet slot 5, in one end wall thereof and an outlet slot 6, in the other end wall thereof to permit a web 7, from a paper-making machine to be fed through said inlet slot 5, and be longitudinally conducted through said casing to be passed out of the casing through the outlet slot 6. The casing 4, is made of any suitable kind of material and is furnished with an insulating lining 8, to prevent radiation of heat.

The supporting frame 2, is provided with a plurality of pairs of oppositely disposed bearings 9, located directly above the supporting legs 3, the apertures in said bearings registering with suitable apertures in the casing 4, to permit the axle ends of a plurality of transversely disposed parallel rollers 10, to be rotatably journaled in said bearings 9. Said rollers 10, are arranged in groups, each group of rollers having an endless or continuous belt 11, engaged there-around, and made of wire mesh, felt or any

other suitable kind of material. Said belts 11, support and carry the web 7, in a straight path longitudinally through the casing 4. Secured on one of the outer projecting ends of one of the rollers 10, in each group of rollers, is a pinion or gear 12, which is in mesh with another pinion or gear mounted therebelow on a stub shaft or axle 13, on the outer end of which a worm 10 wheel 14, is secured and meshes with a worm 15, integral with or secured on the shaft 16, of a driving motor 17.

Securely mounted within the casing 4, are a plurality of electric heating units or elements which are arranged in pairs between adjacently disposed rollers 10, one heating unit of each pair being mounted above and the other below the web 7. Each of the heating units comprises a pair of oppositely disposed T-bars 18, the flanges of which are rigidly secured on the inner walls of the casing 4, so that the stems 19, thereof are directed inwardly toward one another in a horizontal position. Mounted upon the upper side of each of the stems 19, of the T-bars 18, are a plurality of equidistantly spaced insulating blocks 20. Also rigidly secured upon the under side of each of the stems 19, are a plurality of insulating blocks 21, half as many in number as the number of blocks 20. Connected back and forth to the blocks 20, mounted on oppositely disposed T-bars 18, is a wire element 22, having terminals 23 and 24, as shown in the wiring diagram of Fig. 11. Similarly connected to the blocks 21, mounted on oppositely disposed T-bars 18, is a wire element 25, having terminals 26 and 27. As clearly shown in the wiring diagram the wire element 25, has only half the number of bends, turns or loops as are provided in the wire element 22. Each of the wire elements is independent of one another and have associated therewith a two arm switch 28, which in turn is connected across the main power leads 29 and 30. The switches 28, are so arranged that either one or both of the wire elements 22 and 25, of each heating unit may be connected in circuit as desired independently of one another, thus providing an arrangement whereby the heat in the casing 4, may be readily regulated as desired to provide a graduated temperature within the casing. The insulating blocks 20 and 21, may be secured to the stems of the T-bars by means of bolts 31, or other suitable means.

Mounted upon the top of the casing 4, and communicating with the interior thereof, are a plurality of hoods 32, to which are connected pipes 33, the outer end of each of which is attached to a suction pump 34, mounted on the floor 1, at the side of the drier unit and adapted to draw air and steam from the interior of the casing 4, said 60 steam being formed by the hot air in the

drier unit absorbing the moisture from the web 7, during the drying process of said web in its passage through the casing 4, on the endless belts 11. As shown in Figs. 1 and 2, the pipes 33, may have one or more 70 hoods 32, connected therewith, as desired. The pumps 34, may have connected therewith, exhaust pipes (not shown) for the purpose of carrying the exhaust air and steam to a suitable place for discharge. 75

The operation is as follows:

The web 7, which is originally formed in the pulp mixing parts of the paper-making machine is conveyed on an endless belt to the drier unit, where the web 7, is permitted to 80 enter the casing 4, through the inlet slot 5. The belts 11, which run over the rollers 10, are of course set in motion by the driving motors 17, through the gear connections. The various wire heating elements 22 and 85 25, are heated by electricity when the switches 28, are closed to permit the electric current to run from the main leads 29 and 30, through said wire heating elements, which soon become heated and radiate their 90 heat to heat the air within the casing 4. The various heating elements are independent of one another and may thus be connected as required to afford a ready means for regulating the distribution of heat with 95 in said casing.

The suction pumps 34, may be operated by any suitable source of power, and when in operation tend to draw the heated air out of the casing 4, through the hoods 32 and the 100 pipes 33, to be exhausted into the atmosphere or if desired into any suitable type of device adapted to utilize the exhaust heat units.

With the various mechanisms of the drier 105 in operation as described the damp wet web 7, enters the casing 4, through the slot 5, and is conveyed upon the continuous wire mesh belts 11, disposed longitudinally with respect to one another within said casing. 110 The web 7, follows a straight path longitudinally through the casing 4, and passes out of the casing through the outlet slot 6, on to the calendar rolls of the paper-making machine. The web 7, in its passage through 115 the casing 4, is conducted between the upper and lower electric heating elements which are arranged in pairs within said casing. The air within the casing which is heated by the electric heating elements tends to absorb 120 the moisture from the moving web 7, thus drying said web and forming a steam which is drawn from the casing through the hoods 32 and pipes 33, by the suction pumps 34, thereby permitting a fresh supply of air to 125 enter the casing 4. By such an operation a continuous current of heated air moves through the casing 4, around the web 7, and rapidly dries said web uniformly throughout as the same progresses through the cas- 130

ing carried by the belts 11. The belts 11, of course, may be made of felt or any other suitable material and when made of wire, said belts as shown in the modified form of 5 belt conveyer of Fig. 12 may if desired be of different wire mesh starting with a belt 11^a of fine wire mesh at the entrance end of the casing, with each succeeding belt 11^b, 11^c and so forth being of a coarser mesh toward the exit end of the casing, thus permitting the heated air to contact both surfaces of the web to dry the same uniformly and rapidly.

It will of course be understood that numerous details of construction may be varied through a wide range without departing from the principles of this invention, and I therefore do not purpose limiting the patent granted otherwise than necessitated by the 20 prior art.

I claim as my invention:

1. A drier embracing an insulated casing adapted to permit a wet material to be drawn therethrough, electric heating units 25 aligned longitudinally within the casing above and below the material to dry the same, means for regulating said heaters independently of each other, and means connected with the casing to drive the hot air 30 and steam therefrom.

2. A drier comprising an insulated casing, a plurality of belts arranged linearly one after the other within the casing for conveying a material through said casing, and 35 means within the casing for drying the material as it is conveyed through the drier.

3. A drier comprising a casing, electric heaters arranged longitudinally therein, a switch means connected therewith for regulating the same independently of each other for obtaining graduated temperatures in the casing, belts disposed longitudinally within said casing for carrying a web between said electric heaters to dry the web in its passage 40 through the drier, and means connected with the casing for drawing off the hot air and steam.

4. A drier embracing a casing, electric heaters therein for heating the air within said casing, belts within said casing arranged longitudinally with respect to one another, means for operating said belts, said belts adapted to carry a web longitudinally through said casing through the heated air therein to uniformly dry said web by drawing the moisture therefrom, and mechanisms connected with said casing adapted to draw the vapor-laden air therefrom. 55

5. A drier unit for use with a paper-making machine, said drier unit comprising a 60 casing, a plurality of hoods thereon, suction pumps connected therewith, heating means longitudinally arranged in said casing, belts longitudinally disposed within said casing adapted to carry a web to be dried longitudinally through said casing between said heating means, said heating means heating the air within said casing to absorb the moisture from said web in its passage through the casing, said suction pumps adapted to 65 draw the vapor-laden heated air from said casing through said hoods to permit a uniform drying of said web. 70

6. In a device of the class described, a casing, a plurality of rollers transversely disposed therein, arranged in groups, an endless belt trained around each group of rollers, means connected with certain of said rollers for rotating said belts to carry a web longitudinally through said casing in a 75 straight path, heaters arranged longitudinally in said casing for heating the air therein to absorb the moisture from said web to dry said web, and means for drawing said vapor-laden air from said casing thereby 80 causing a movement of the heated air through said casing around said web. 85

In testimony whereof I have hereunto subscribed my name in the presence of two subscribing witnesses.

JOHN E. ALEXANDER.
